LIQUID DISPENSING DEVICE

Filed Aug. 30, 1928

UNITED STATES PATENT OFFICE

JACOB J. ROBINSON, OF WASHINGTON, DISTRICT OF COLUMBIA

LIQUID-DISPENSING DEVICE

Application filed August 30, 1928. Serial No. 303,031.

This invention relates to liquid dispensing devices particularly adapted for use in barber shops.

It is a well known custom in barber shops, when shampooing a customer, to have the customer sit on a stool adjacent a basin whereby water can be sprayed onto his head and the liquid shampoo applied. Heretofore such liquid shampoo has been contained 10 in bottles and these bottles are kept on shelves or at places other than at the basin. As a result, it is necessary for the barber to obtain the liquid shampoo from the shelf or other place while the customer is waiting 15 at the basin, then to apply the shampoo to the customer and afterwards replace the shampoo on the shelf.

One of the principal objects of my invention is to provide a device, containing a 20 shampoo liquid, which is adapted to be removably attached to a support mounted on the basin whereby the attendant may immediately apply the liquid to the customer.

Another object of the invention is to provide such a device which may be supported 25 centrally between two connected bowls in a manner to permit of the device being swung into operative position for use in connection with either bowl.

30 A further object of the invention is to provide such a device which is adapted to be attached to the upper end of the support whereby the container may be swung into either an operative or inoperative position 35 as desired and whereby said container may be removed whenever necessary.

With these and other objects in view which will more fully appear, the nature of the invention will be more clearly understood 40 by following the description, the appended claims, and the several views illustrated in the accompanying drawings.

In the accompanying drawings:

Figure 1 is a sectional view of a double 45 washstand showing the application of my invention.

Figure 2 is an enlarged sectional view of the device showing its application to the support,

50 Figure 3 is an enlarged detailed sectional

view of the upper end of the container, and

Figure 4 is a detailed sectional view taken on the line 4—4 of Figure 2.

Like reference numerals designate corresponding parts throughout the several figures of the drawings.

Referring to the accompanying drawings, I have illustrated a washstand A which in the form shown is of the double type and consists of a column 5 for supporting a pair 60 of wash basins 6—6. Mounted on the stand 5 intermediate the wash basins is a standard 7 having a shoulder 8 adjacent the upper end thereof and projecting above the shoulder 8 is a spherical head 9 which is connected to the shoulder by a reduced neck 10. 65

Removably attached to the standard 7 is my improved liquid shampoo device B. This device includes a container 11 having a closed circular bottom 12 and a peripheral 70 wall 13, said container having an open top which is closed by a flexible diaphragm indicated as a whole by the character C. The container 11 is provided with a discharge spout 14 which communicates with 75 the wall 13 at a point adjacent the bottom 13 of the container. This spout preferably extends upwardly from the bottom of the container from a point adjacent the top thereof and thence downwardly and outwardly. The diaphragm C comprises a flexible annulus 15 of rubber or the like, the peripheral edge of which overlaps the upper end of the container and is secured thereto by a clamp ring 16. The inner edge 80 of the annulus overlies a metal disc 17 and is clamped thereto by means of a clamp plate 18. The disc 17 is provided with a filler opening 18a from which rises a filling neck 19 having a closure 20 attached thereto by screw threads, the neck 19 passing upwardly through an opening 21 formed in the clamping plate 18. Attached to the

disc 17 and extending upwardly through an opening 22 formed in the clamping plate 95 18 is a stem 23, and to the upper end of this stem is connected a head 24, the stem and the head conjointly forming a hand piece. The stem 23 is provided with a passage 25 which communicates with the interior of 100

the container and with the atmosphere. The stem is centrally located with respect to the diaphragm. In order to secure the inner marginal edge of the flexible annulus 15 between the disc 17 and the clamping plate 18, I have provided a clamping nut 26 which is threaded onto the stem 23. A spring arm 27 has one end 28 riveted or otherwise secured to the wall 13 of the container at a point diametrically opposite the discharge spout 14. This arm 27 extends upwardly and outwardly and thence laterally above the diaphragm and is provided at a point adjacent its free end with an elongated opening 28 adapted to receive the stem 23. Clamping nuts 29-29 are threaded onto the stem 23 and cooperate with the clamping nut 26 to permit the arm 27 to have free sliding movements therebetween. The spring arm 27 functions to return the diaphragm to its normal position and also functions as a handle for the purpose of either carrying the container when removed from its support or 25 for swinging the container about its support.

In order to removably attach the device to the supporting standard 7, I have provided a clamp D which consists of a rigid arm 30 and a spring arm 31. The rigid arm 30 is fixedly secured to the bottom 12 of the container and includes a downwardly extending portion and a laterally extending terminal portion, the latter being provided 35 at its free end with a longitudinally extending slot 32. The spring arm 31 normally extends downwardly towards the rigid arm, as shown in Figure 2, and this spring arm is provided with an opening 33 for receiving 40 the head 9 of the supporting standard 7. The width of the slot 32 is just sufficient to receive the neck 10 of the standard 7, and consequently the rigid arm is incapable of vertical movement relative to the standard 45 but is capable of horizontal movement relative thereto.

In practice when it is desired to attach the container to the standard 7, the free end of the rigid arm is guided into engagement with the neck 10, and simultaneously the spring arm 31 will ride over the head 9 until the opening 33 engages the head 9. The rigid arm 30 will then become seated on the shoulder 8 and the flexible arm 31 55 will cooperate with the head 9 to hold the container against tilting action, either permitting the container to be swung about the standard 7 to any desired position, or to be removed therefrom by simply elevating the 60 spring arm 31 from engagement with the head 9 and moving the entirety towards the left as viewed in Figure 2.

When it is desired to dispense the liquid from the container, the attendant places the 65 palm of his hand upon the head 24 thereby

closing the passage 25 from the atmosphere. Pressure is then applied on the hand piece, and consequently the diaphragm will be moved downwardly through the medium of the flexible annulus 15 thereby permitting the air within the upper portion of the container to force the liquid outwardly through the discharge spout 14. This downward movement of the diaphragm flexes the spring arm 27 and when the attendant releases the hand piece, the diaphragm tends to return to its normal position and is assisted in this movement by the spring arm 27. This operation, of course, is repeated as often as it is desired to dispense the 80 liquid.

It is of course to be understood that the details of structure and arrangements of parts may be variously changed and modified without departing from the spirit and scope of my invention.

I claim:

1. In a liquid dispensing device, the combination with a standard having a head connected to the upper end thereof by a reduced neck, a liquid dispensing container, and a clamp carried by the bottom of the container for detachable connection with the standard, said clamp including a laterally extending rigid arm having a slotted free end for receiving the neck of the standard, and a laterally extending spring arm disposed above the rigid arm and provided with a socket to receive the head of the standard.

2. In a liquid dispensing device, the combination of a liquid container having an open top and provided with a discharge spout on one side of the container, a flexible diaphragm attached to the top of the container, a hand piece extending upwardly from the center of the diaphragm, the diaphragm and the hand piece being conjointly formed with a passage communicating with the interior of the container and with the atmosphere, and a spring arm connected at one end to the container at a point opposite the discharge spout and at its other end to the diaphragm and shaped to function as a combined handle and a means for assisting the return movement of the diaphragm.

3. In a liquid dispensing device, a liquid dispensing unit, and means to swivel-mount the unit for rotation about a vertical axis to enable dispensing of liquid in various directions, said mounting means comprising a shoulder-support-equipped-standard, a mounting knob extending above the shoulder-support and joined thereto by a reduced neck, a mounting arm carried by the unit and having its end bifurcated to straddle the reduced neck, and a snap spring carried by the unit and opposed to the bifur-

cated end of the arm to yieldably engage said knob when in the said bifurcation.

4. In a liquid dispensing device, a liquid dispensing unit, and means to swivel-mount the unit for rotation about a vertical axis to enable dispensing of liquid in various directions, said mounting means comprising a shoulder-support-equipped-standard, a mounting knob extending above the shoulder-support and joined thereto by a reduced neck, a mounting arm carried by the unit and having its end bifurcated to straddle the reduced neck, and a snap spring carried by the unit and opposed to the bifurcated end of the arm to yieldably engage said knob when in the said bifurcation, said spring having a socket therein to receive the knob and secure the unit against inadvertent removal from the standard while permitting rotative movement of said unit about the axis of the standard.

5. In a liquid dispensing device, a liquid dispensing unit, and means to swivel-mount the unit for rotation about a vertical axis to enable dispensing of liquid in various directions, said mounting means comprising a shoulder-support-equipped-standard, a mounting knob extending above the shoulder-support and joined thereto by a reduced neck, a mounting arm carried by the unit and having its end bifurcated to straddle the reduced neck, and a snap spring carried by the unit and opposed to the bifurcated end of the arm to yieldably engage said knob when in the said bifurcation, said spring having a socket therein to receive the knob and secure the unit against inadvertent removal from the standard while permitting rotative movement of said unit about the axis of the standard, said spring being projected beyond the said bifurcation and upturned for the purpose described.

In testimony whereof I hereunto affix my signature.

45

JACOB J. ROBINSON.
